CLAIM

The ornamental design for a telephone for automobiles, substantially as shown and described.

DESCRIPTION

FIG. 1 is a front, top, and right side perspective view of a telephone for automobiles showing my new design, numerals being displayed on an upper section of a handset during a turn-ON time for illustrative, environmental association purposes only;

FIG. 2 is a front elevational view thereof;

FIG. 3 is a rear elevational view thereof;

FIG. 4 is a top plan view thereof, numerals being displayed on an upper section of a handset during a turn-ON time for illustrative, environmental association purposes only,

FIG. 5 is a right side elevational view thereof;

FIG. 6 is a left side elevational view thereof; and

FIG. 7 is a front, top, and right side perspective view with a handset removed from a telephone base.

FIG. 1

FIG. 4

FIG. 2

FIG. 3

FIG. 5

FIG. 6

FIG. 7
